UNITED STATES PATENT OFFICE.

OLIVER F. CONKLIN, OF DETROIT, MICHIGAN, ASSIGNOR TO REMY ELECTRIC COMPANY,
OF ANDERSON, INDIANA, A CORPORATION OF INDIANA.

SELF-LUBRICATING BEARING.

1,341,415.

Specification of Letters Patent. Patented May 25, 1920.

Application filed July 10, 1917. Serial No. 179,641.

To all whom it may concern:

Be it known that I, OLIVER F. CONKLIN, a citizen of the United States, residing at Detroit, county of Wayne, and State of Michigan, have invented certain new and useful Improvements in Self-Lubricating Bearings, of which the following is a full, clear, and exact description.

This invention relates to improvements in self-lubricating end bearings of the type particularly adaptable for dynamos and motors such as are used for electric generating and starting upon automobiles.

The present invention more particularly relates to improvements in the construction of the wick type of oiler, and the invention particularly resides in certain novel constructions which make the oiler entirely self-contained in the end casting of the machine. Other features include improvements in the wick carrier whereby the wick may be readily replaced when worn. Other objects reside in the provision of a wick oiled bearing of such character that any excess oil which might work along the shaft and be spattered inside or outside of the machine would be drained back to the oil reservoir in the end plate or casting.

In the drawings:

Figure 1 shows in central section two end bearings and end plates for an electric machine such as a dynamo or motor.

Fig. 2 is a sectional detail view taken on line 2-2 of Fig. 1.

In more detail in the drawings 10 is the frame of the electric machine. On each end of the frame there are bolted end plates 11 and 12. These end plates have cast integrally in the lower part thereof an oil reservoir 13. The center of the end plate is bored out to receive a bronze bearing bushing 14. This bearing bushing supports the armature shaft 15 of the machine. At the ends of the bushing 14 the end plate is cupped with annular grooves 16 and 17. Adjacent the inner cupped depression or annular groove 16 the shaft 15 is grooved with two annular grooves, 17^a. Carried by the shaft between these grooves there is a felt ring 18. The function of this felt ring is to catch any oil which may be entrapped in the grooves 17^a and to throw this oil by centrifugal action into the annular groove 16.

From the cupped depression 16 the excess oil is drained back through ducts 18^a to the

oil reservoir 13 in the end casting. As illustrated in the drawings the felt ring 18 is omitted for the right hand annular groove 17, but a felt ring could be provided at this point if desired. 60

At the bottom of end plate 12 a tapped hole 19 extends through the walls of the oil reservoir. This threaded hole receives the wick carrier which will now be described: 65

The wick carrier comprises a bottom threaded plug portion 20 and an upwardly extending tube portion 21. The plug portion 20 forms a closure for the bottom of the oil reservoir and also forms an abutment for a spring 22 which is located within the tube 21. The function of this spring is to urge the wick 23 upwardly in the tube and to resiliently press the end of the wick against the rotating shaft. It will be understood that the wick passes through an opening in the upper part of the oil reservoir and through the bushing 14. In order to admit oil to the lower end of the wick the tube 21 is drilled as shown at 24. The wick carrier just described may be readily removed for replacing wicks by simply applying a screw-driver to the plug 20. In order to fill the oil reservoir I provide a dust excluding oiler 25 of the usual form. 75

The construction on the left hand side of the machine, as illustrated in Fig. 1, is identical with the previous construction except that the reservoir 13^a extends up past the end of shaft 15. This construction necessitates tapping the hole 19^a at an angle in order that the wick 23 will extend to the center of the bearing. 80

Another feature which is slightly different is that the tube 21 extends up in a depending shroud 27 which is integral with the end plate 11. 85

With both of the constructions, namely the right and left hand construction, I preferably provide an oil groove 28 which is 90 adapted to distribute the oil from the wick 23 along the bearing 14.

The construction described has proved advantageous in many respects over the previous constructions, the oil reservoir being 105 cast integral with the end plate cheapens the manufacture of the end bearings and permits the use of the oil returning in ducts 18. Furthermore, all depending parts, such as pressed metal oil wells, are eliminated, 110

These oil wells, which are external, have frequently become broken off when the apparatus is in use. Furthermore, the oil reservoir 13 is better adapted to contain a large supply of oil so that the times of refilling need not be very frequent.

It is understood that my invention may be modified in various ways as will occur to those skilled in the art and what I claim as my invention is more particularly pointed out in the appended claims.

I claim:

1. An end bearing for a shaft of an electric machine, comprising an end plate for said machine, said plate having therein an integral oil reservoir, a bearing carried by the plate adapted to receive a shaft, said bearing and end plate having an opening extending into the reservoir and a wick extending from the reservoir through the opening and carrying the oil to the shaft, and means mounted in the reservoir for supporting and guiding said wick.
2. An end bearing for a shaft of an electric machine, comprising an end plate for said machine, an integrally cast oil reservoir in said end plate, a bearing carried by said plate and adapted to receive a shaft, a wick projecting through the bearing contacting with the shaft and extending into the reservoir, annular oil catching depressions in said plate about the shaft at the ends of the bearings and oil ducts leading back from said depressions to the reservoir to return excess oil thereto, and means mounted in the reservoir for supporting and guiding said wick.
3. An end bearing for dynamo electric machines, comprising an end plate for said machine, an integrally cast oil reservoir therein, a bearing carried by said plate, a shaft extending therethrough, annular depressions in said shaft adjacent the end of the bearing, annular depressions in said plate adjacent the end of the bearing, a felt ring carried by the shaft adapted to collect excess oil therefrom and deposit the oil in the depressions in the plate and drain back ducts leading from said depressions to the oil reservoir to return the excess oil thereto, and means mounted in the reservoir for supporting and guiding said wick.
4. An end bearing for a dynamo electric machine, comprising an end plate therefor, said plate having an oil reservoir integral therewith, a bearing carried by the end plate, and having an opening for an oiling wick, a wick retaining tube threaded into the reservoir and projecting upwardly toward the bearing, a wick in said tube and a spring in said tube abutting against the closed lower end thereof and against the wick for urging the wick against the shaft rotating in the bearing.
5. An end bearing for an electric machine,

comprising an end plate therefor, said plate having an oil reservoir integral therewith, a bearing carried by said end plate adapted to support the machine shaft, said end plate having a threaded opening in the lower end of the end plate, a wick retainer threaded in said opening, said retainer comprising a threaded end portion constituting a closure for the bottom of the reservoir, a tube projecting upwardly therefrom to carry a wick, an opening in said tube to admit oil to the inside of the tube from the reservoir, a spring in said tube resting against the closed end thereof and a wick in said tube urged against the shaft in the bearing by said spring.

6. An end bearing for a dynamo electric machine, comprising an end plate therefor, said end plate having an oil reservoir integral therewith, a bearing carried by the end plates and having an opening for an oiling wick, a wick retaining tube threaded into the reservoir and extending upwardly toward the bearing, a wick in said tube, a spring in said tube abutting against the closed lower end thereof and against the wick to urge the wick against a shaft rotating in the bearing, annular depressions in said end plate adjacent the ends of the said bearings and return ducts leading from said depressions to the oil reservoir, said return ducts being adapted to carry back any excess oil caught in said depression.

7. In a device of the character described, the combination with a bearing; of an oil reservoir therefor; a wick extending from the reservoir and through the bearing; and wick guiding means removably mounted within the reservoir.

8. In a device of the character described, the combination with a bearing; of an oil reservoir therefor; a wick extending from the reservoir and through the bearing; and a wick guiding and supporting member detachably mounted within the reservoir.

9. In a device of the character described, the combination with a bearing; of an oil reservoir therefor; a wick extending from the reservoir and through the bearing; a wick guiding and supporting member screwed into the bottom wall of the reservoir and having a hole therethrough located above the bottom of the reservoir; and a spring located in said wick guide for maintaining said wick above the bottom of the reservoir and for yieldingly maintaining the wick against a shaft in said bearing.

10. In a device of the character described, the combination with a bearing; of an oil reservoir therefor; a wick extending from the reservoir and through the bearing; and a drain plug for the reservoir constructed and arranged to support and guide the wick.

11. In a device of the character described, the combination with a bearing; of an oil

reservoir therefor; a wick extending from the reservoir and through the bearing; wick guiding means removably mounted within the reservoir; and means carried by the 5 guide for yieldingly urging the wick toward the bearing.

12. In a device of the character described, the combination with a bearing; of an oil reservoir therefor; a wick extending from

the reservoir and through the bearing; a 10 tubular wick guide removably mounted within the reservoir and adapted to receive the wick; and a coil spring mounted within the wick guide for yieldingly urging the wick toward the bearing.

In testimony whereof I hereunto affix my signature.

OLIVER F. CONKLIN.
